UNITED STATES PATENT OFFICE.

IVERN ANTHONY JACOBS, OF COLLIE, WESTERN AUSTRALIA, AUSTRALIA.

SELECTIVE MIXING FAUCET.

Application filed January 13, 1925, Serial No. 2,181, and in Australia October 7, 1924.

This invention provides an effective and conveniently operated machine for dispensing those kind of beverages from the bulk which are composed of soda water and different flavoured syrups and said machine is adapted to be installed on a counter or the like. It is obvious that the reservoirs for the soda water and the flavouring syrups may be connected to the machine in any approved manner. The dispensing of the different flavoured beverages is effected by the same handle, which latter, through a push plate, simultaneously operates the inlet valves for the supply of the soda water and the selected syrup.

In some machines made in accord with this invention I employ only that portion and those members which are requisite for the sole dispensing of the soda water.

An essential feature of this invention resides in the structural means and formation made and provided whereby the soda water at high pressure is directly fed from the bulk into an expansion or relief chamber formed therefor in the casing of the machine and in said chamber the soda water is given instant relief and expansion and its initial pressure is thereby effectively broken up and reduced to enable it to flow at such approved and reduced pressure into the drinking glass through the outlet of the chamber—said outlet having a greater transverse area than the transverse area of the inlet for the soda water. The soda water upon its entry into the said expansion chamber strikes against the front inner wall of the latter and said wall is preferably formed with an overhang shoulder whose object is to prevent undue upward splash of the inflowing soda water which would otherwise baffle the entry of the selected syrup into the said chamber and the inlet for the said syrup is positioned at a greater radius than but adjacent to the inlet for the soda water and said chamber becomes in practice a mixing chamber for the beverage.

Preferably the line of the inlet for the soda water is positioned rectangular to the expansion chamber and the outlet for the beverage, but it is obvious that said respective lines of inlet and outlet may be positioned at an angle other than a right

angle and I do not limit or restrict myself to the exact or precise angle of alignment of said inlet and outlet.

The structural features and use of the invention will now be described with the aid of the attached drawings wherein Fig. 1 is a sectional elevation showing the operative members in their idle position, the respective valves being closed. In said view for sake of clearness one syrup valve is shown and the working position of the hands is indicated by broken lines. Fig. 2 is a front elevation of same.

In this specification the description of the construction and operation of a selected syrup, valve and its related parts is also applicable to each of the plurality of syrup valves.

Referring to said drawings, the invention comprises a casing as $a-a^1$ adapted to be installed on a standard bracket or other like anchorage as a^2 . This casing may be made in one integral piece or made in two portions as a and a^1 as shown in which latter case the front portion a is made with a rear stem a^3 adapted to pass through the rear portion a^1 of the casing and be thereat secured by lock nut a^4 . Further said portions may be secured together by holding flanges and studs as a^5 . Within said casing are housed the inlet valves for the supply of the soda water and the plurality of syrups or flavouring essences.

Within this casing $a-a^1$ is formed the chamber b whose throat b^1 acts as the outlet for the beverage said chamber providing relief or expansion for the high pressure soda water upon its entry thereinto from its bulk container (not shown). The inner front wall of said chamber is made with an overhang shoulder b^2 which minimizes any upward splash of the inflowing soda water. The soda water is led from its container by pipe b^3 to said chamber b the inlet for same being controlled by the horizontally operative valve c of a self-sealing type which works in its seat c^1 formed in the rear portion a^1 of the casing. The stem c^2 of said valve c extends forwardly and is formed therein with a duct or passage c^3 which allows of the entry of air to destroy vacuum in the chamber b .

as soon as the beverage is dispensed and the handle returned to its idle position as seen in full lines in Fig. 1.

During the dispensing action the push

plate hereinafter mentioned when in its operative position seals this duct c^3 and prevents any outward escape of liquid. On the front portion of the valve stem c^2 is

10 secured a cap c^4 , which is guided and held within a cavity c^5 formed therefor in the portion a of the casing, said cap c^4 being fitted with an internal spring c^6 whose duty is to return the soda water inlet valve to its closed position as seen in Fig. 1. The

15 plurality of syrup valves as d are also of a self sealing type and work in seats d^1 formed on the rear portion of the casing and have forwardly extending stems d^2 which at their terminals are fitted with

20 caps d^3 held within cavities d^4 formed therefor in the front portion a of the casing, said caps being also provided with spiral springs d^5 which operate to return the valves d to their closed position as shown in Fig. 1.

25 The cap of each syrup valve d is fitted with a screw threaded adjustable plug d^6 in order that the opening of said syrup valve d may be retarded or advanced relatively to the opening of the soda water valve to vary the flavour of the beverage.

The rear casing a^1 is made with a plurality of passages as e each of which by plug controlled pipe as e^1 communicates with a syrup reservoir each of said passages e being provided with an upper and rear removable plug as e^2 to allow of the cleaning and replacement of a syrup inlet valve as d . From each of said passages e any selected syrup is led through the valve controlled in-

30 let into a cavity e^3 and thence into the central or mixing chamber b . The front casing a is formed with an outwardly extending fixed stem f on which is freely and slidably carried a push plate f^1 approximately of semi-circular shape. Said plate f^1 is made with a boss f^2 and provided with a rear operative spiral spring f^3 . The function of said spring is to retire said plate from contact with the cap as c^4 and inset plug d^6 of

40 the respective valves as soon as the working handle g is returned to its idle position as seen in full lines in Fig. 1. The front portion of the boss f^2 of said plate f^1 is made with two flat or nut faces g^1 as seen in Fig. 55 2 to receive and be operatively engaged by the jaws g^2 of the handle g whereby the desired degree of rotation is given to said plate. This plate f^1 is made with the projecting lug g^3 to contact with the adjustable plug d^6 of the selected syrup valve, said plate simultaneously having contact at a lesser radius with the cap c^4 of the soda water valve.

To dispense soda water alone the plate 60 f^1 is sufficiently rotated to bring said lug

93 beyond the lowest positioned syrup valves at either end of the casing and as shown in broken lines in Fig. 2. The handle g is pivoted to a block k^1 by a pin k , the said block being freely held on the fixed stem f by cotter pin k^2 and fitting closely between the front portions of the jaws g^2 of the handle g .

The jaws g^2 are eccentrically positioned with relation to the hinge pin k and have 75 cam shaped faces m which are adapted to engage and exert an inward pushing movement on the slidable plate f^1 .

The operation of the machine in connection with a soda water inlet valve and a 80 selected syrup inlet valve is as follows:—

When the handle g is moved (through block k^1) on the fixed stem k the desired degree of rotation necessary to bring the projecting lug g^3 of the plate f^1 immediately in front of the adjustable plug d^6 of the selected syrup valve d , the said handle g is then pulled outwardly, to the position seen in broken lines in Fig. 1 on its pivot pin k , thereby causing the cam faces m of the jaws g^2 to effect inwardly pushing contact against said plate f^1 which in turn makes like contact at a lesser radius against the cap c^4 of the soda water inlet valve c , said plate f^1 by its lug g^3 having like pushing 95 action against the adjustable plug d^6 of the selected syrup valve d . By the operation of the parts just specified, the valves d and c permit a simultaneous supply of the soda water and syrup from their respective containers into the expansion and mixing chamber b —the beverage flowing through the throat b^1 into a glass p . As soon as the handle g is returned to its normal position the faces m of the jaws g^2 are released from contact with the plate f^1 , the latter being returned to its normal position by the spring f^3 as shown in full lines in Fig. 1.

What I claim as my invention and desire to secure by Letters Patent is:—

1. A machine for dispensing beverages, comprising a casing having a chamber therein formed with a lower outlet throat and an inner, upper overhanging shoulder, said chamber having valve-controlled inlets for the admission of soda water and syrups and in communication with passages provided with removable plugs.

2. A machine for dispensing beverages comprising a chamber formed with a lower outlet throat and an inner upper overhanging shoulder, said chamber also having valve-controlled inlets for the admission of soda water and syrups and in communication with passages provided with means for controlling the open and closed condition thereof, a handle pivotally connected to a front projecting portion of the casing, said handle being formed with jaws eccentrically mounted with relation to the pivotal means,

and a push plate applied to the forwardly projecting portion of the casing and connected to the valves controlling the said inlets, the jaws of the handle being operable to engage a portion of the push plate for disposing the latter in desired operative position.

3. A machine for dispensing beverages comprising a casing having a chamber formed therein and provided with a lower outlet throat and an upper, inner overhanging shoulder, said chamber also having inlets provided with valves for controlling the admission of soda water and syrups into the chamber and in communication with passages provided with movable means for controlling the open and closed condition thereof, the casing also having a forwardly projecting stem, a spring-controlled push plate radially and slidably mounted on the said stem and formed with a projection, the means for controlling the open and closed condition of the said inlets having outer caps with portions adapted to be engaged by the projection of the push plate to control the inlet of soda water and the selected syrup into the chamber.

4. A machine for dispensing beverages comprising a casing having a chamber formed therein with an outlet throat at its

lower portion and an upper, inner overhanging shoulder, the said chamber having passages communicating therewith and forming inlets provided with valves for controlling the admission of soda water and syrups into the said chamber, the soda water inlet valve being spring controlled and provided with a stem having a duct or passage, and a push plate mounted to cooperate with the said spring-controlled soda water inlet valve and close the passage of the stem of said valve.

5. A machine for dispensing beverages comprising a casing having a chamber formed therein with an outlet throat at its lower portion and an upper, inner overhanging shoulder, the said chamber also having passages communicating therewith to provide inlets each having a spring-controlled valve mounted therein for the admission of soda water and syrups into the said chamber, each spring-controlled syrup inlet valve having a cap provided with an adjustable plug, and a push plate mounted to cooperate with the plugs of the said spring-controlled syrup inlet valves.

In testimony whereof I have hereunto set my hand.

IVERN ANTHONY JACOBS.
